UNITED STATES PATENT OFFICE

103,695

DESIGN FOR A SHOE OR SIMILAR ARTICLE

Herbert Shapiro, Newton, Mass.

Application December 23, 1936, Serial No. 66,711

Term of patent 3½ years

To all whom it may concern:

Be it known that I, Herbert Shapiro, a citizen of the United States of America, residing at Newton, in the county of Middlesex and State of Massachusetts, have invented a new, original, and ornamental Design for a Shoe or Similar Article, of which the following is a specification, reference being had to the accompanying drawing forming a part thereof,

The figure is a side view of a shoe showing my new design.

The opposite side of the shoe presents substantially the same appearance as the side shown.

I claim:

The ornamental design for a shoe or similar article substantially as shown and described.

HERBERT SHAPIRO.
